ATTORNEYS.

UNITED STATES PATENT OFFICE

WILLIAM L. LENGEL, OF READING, PENNSYLVANIA, ASSIGNOR TO THE LENGEL-PENCIL CO., OF READING, PENNSYLVANIA, A CORPORATION OF PENNSYLVANIA

SPLIT-FOOT STOCKING

Application filed December 27, 1926. Serial No. 157,360.

My invention relates particularly to the well known split-foot type of stockings in which top and bottom areas are reciprocatively knitted with interlooped selvages or sutures at the sides and above the heel pocket.

The approximate half-circle of needles which are employed in the operation of forming the heel pocket, are commonly employed also in knitting the split-foot sole and the usual high-splice above the heel; the continuous suture lines being bent at the apex points of the heel pockets, and the structure there being relatively weak and unsatisfactory. My invention provides for simplifying and effectively improving the construction both as to strength and appearance, as will be fully described in connection with the accompanying drawing illustrating an embodiment thereof; and the novel features being clearly defined in the subjoined claims.

Fig. 1 is a diagrammatic view of a portion of a tubular-knit stocking embodying my invention; the additional shorter wales knitted, in my improved construction, beyond the apex points of the heel pocket so as to unbrokenly connect the otherwise separated sole and high-splice portions of the stockings, being adapted to produce a preferred curvature of the deflected suture line.

Fig. 2 is a diagrammatic view showing the usual circular series of needles employed in tubular knitting, and illustrating in connection with the following explanation my improved method of knitting.

Fig. 1 indicates mainly an ordinary split-foot stocking as made on a circular series of needles indicated in Fig. 2; the tubular-leg portion 5 being knitted upon the full circle of needles with substantially the rear-half producing the high-splice 6, and the heel pocket 7. The top and sole of the so-called split-foot are not knitted round-and-round but are simultaneously knitted reciprocatively of two yarns as usual the split portion 8 of one yarn upon said rear-half of the needles, and the top portion 9 of the second yarn upon the front-half, with a suture 10 at each side; and this split knitting is also employed in making the high-spliced portion of the leg, a reinforced yarn being added in such high

splice only and forming a selvage edge at the suture line with the front-half of the leg, in place of the usual high-splice float ends.

In resuming knitting upon all the needles, as at the line α — c , for the forming of the foot, it will be readily understood that side points of special strain and relative structural weakness naturally develop at the angular junctions of the split high-splice and split-foot with each apex 15 of the heel pocket 7; and the object of my invention is to satisfactorily eliminate such structural weakness at these points, and at the same time improve the appearance of the product, by providing suture lines having curved portions 10^a spaced away from each apex point 15 of the heel pocket, with intervening rear-half yarn wales 16 joining the high splice to the split-foot sole, as indicated.

As will clearly appear by reference to Figs. 1 and 2 of the drawing, I effectively accomplish this by raising certain of the needles of the front-half or instep portion of the stocking to knit for determined courses with the yarn of the rear-half or high-splice needles, so as to provide substantially isosceles triangular reinforced extensions composed of varying length additional rear-needle knitting wales 16 with their base lines spaced from the pointed heel pocket junctions 15 and their respective apexes corresponding with the latter; such wales 16 preferably starting at different points in the lower part of the high splice and terminating at different points in the rear-part of the sole as indicated, so as to form said curved portion 10^a in the suture line 10.

In Fig. 2 α indicates the rear-half circle of needles and γ the front-half circle as commonly employed in circular knitting machines; the half circle α being employed as usual, in knitting the rear-half of the stocking, the high-splice heel, heel and toe pockets, and the bottom of the foot, and the half circle γ the front-half of the leg, instep and top portion of the foot as usual. In the construction shown however, I prefer to employ only part of the needles α in the high-splice, heel-pocket and foot-bottom portion of the stocking to produce reduced width therein as par-

ticularly popular in the trade, certain needles x' and x^2 at each end of the half-circle being adapted to ordinarily knit with the half-circle y during the reciprocative knitting operation except as modified, as hereinafter more fully explained to produce the curved suture line 10^a.

The stocking thus produced is circularly knit of main yarn to the beginning of the 10 high-splice; then reciprocative knitting begins with two main yarns, one for each half-circle of needles, and one additional or high-splice yarn added to the needles x , except needles x' and x^2 which knit with the needles 15 y on the front-half main yarn, to the beginning of the curved suture line 10^a; then gradually end needles of x' and x^2 adjacent the main series x , are manipulated to discontinue knitting of the yarn of needles y and engage 20 and knit the yarn of needles x until all x' and x^2 are thus engaged at the beginning of the heel pocket or line $a-b$ of Fig. 1; then all needles y plus x' and x^2 are raised out of 25 action and reciprocative knitting on the needles x , less x' x^2 , with gradual withdrawal and return of end needles produces the usual heel pocket, ending at the line $a-c$, Fig. 1; then needles y , x' and x^2 are returned to knitting, x' and x^2 continuing knitting with the 30 needles x and reciprocative split-foot knitting continued with gradual withdrawal of end needles of x and x' adjacent needle series y from the half-circle x back to half-circle y to complete curved suture line 10^a; by formation 35 of wales of different length ending in said suture line when all needles x' and x^2 are thus returned to action with needles y , the less than half-width split-foot bottom 8 and more than half-width top 9 of the stocking 40 are produced by continued reciprocative split-foot knitting; prior to producing the usual toe pocket 11 needles x and x' may again be gradually returned to action with needles x , or preferably, as shown, a band of 45 circular knitting 12 may be produced prior to knitting the toe pocket in well known manner.

To manipulate the needles in the production of a stocking as above described, I employ any well known type of circular machine adapted for split-foot knitting and divide the needles as usual in half-circle series, those marked x having short butts, and those marked y having long butts, their operation 50 by the machine cams being as heretofore and requiring no further description. In Fig. 2, 19 represents the usual instep or dividing cam for separating the two half-circle of needles, 20 represents usual knitting cams 55 employed for circular knitting on all the needles, or reciprocative knitting on the needles x ; while 21 represents additional knitting cams thrown into action during reciprocative split-foot knitting and employed to 60 actuate the needles y , end needles of both se-

ries x and y always engaging, as usual in split-foot knitting, the yarn of both half-circle series so as to form a seamless tube. In order to control the needles x' and x^2 in their special operation with either half-circle series x or y , and to make such changes singly or in groups of each series x' and x^2 , I preferably control them as indicated in Fig. 2, by jacks 25 and 26 and jack-actuating cams 27 and 28; said jacks, as shown, having butts of different length for each needle, or said butts being arranged in adjacent pairs or groups of different length but corresponding in each series x' and x^2 , and said cams 27 and 28 having stepped movements towards said jack butts so as to step-by-step in successive courses or spaced courses actuate an increasing or decreasing number of jack butts or groups of butts.

In the stocking shown in Fig. 1, circular knitting on all the needles by knitting cams 20 produces the seamless fabric to the beginning of the high splice. At this point the needles are divided and additional knitting cams 21 and a separate yarn therefor introduced for producing a seamless split-foot fabric by reciprocative knitting on each half-circle of needles with the end needles cooperating to unite said halves; the jack cams 27 and 28 also acting to cause needles x' and x^2 to be operated with needles y by knitting cams 21. At the beginning of the curved suture line 10^a, the jack cams 27 and 28 are moved one step to actuate end needles or groups thereof of x' and x^2 adjacent the main group x so as to avoid action by knitting cams 21 and instead receive action with needle group x and its yarn by knitting cams 20; further inward step movements of cams 27 and 28 bring into action of said cams 20 the other needles of x' and x^2 until all thereof are acting with needle group x and its yarn on cams 20, at which point the beginning of the heel pocket is reached on line $a-b$ of Fig. 1. At this point all needles y and needles x' and x^2 are raised out of action by cams 19, 27 and 28 and remain so raised during the usual reciprocative knitting of the heel pocket by knitting cams 20. At the end of the heel pocket all needles y , x' and x^2 are restored to knitting by proper manipulation of cams 19, 27 and 28, and reciprocative tubular knitting resumed; jack cams 27 and 28 step-by-step reversing the movements of the needles x' and x^2 so as to gradually return them to action with needles y and cam 21, with which latter they remain during the entire remaining portion of the bottom foot portion of the stocking. Before the toe pocket portion is reached jack cams 27 and 28 may again gradually move needles x' and x^2 to action with needles x and knitting cams 20, but I prefer as shown, to discontinue reciprocative knitting near the toe pocket, withdraw additional cams 21 and resume circular knitting 130

on all the needles to form the band 12 preliminary to forming the usual toe pocket.

The additional wales 16 thus produced by the heavier reinforced high-splice and reinforced foot yarns beyond the heel pocket junction 15 produces the curved suture line 10^a, protecting the weak apex point of the heel pocket ordinarily found in stockings as commonly made, and giving a pleasing curved line of junction at the point of the leg and foot instead of the heretofore angular connection.

What I claim is:—

1. The improved method of knitting high-spliced split-foot stockings which consists in gradually transferring end needles from the front split foot knitting action into the rear high splice knitting action preliminary to starting the knitting action of the heel pocket; then knitting the heel pocket by narrowing and widening reciprocative action upon a portion of the needles less than the maximum then employed in the high splice; and then resuming split foot knitting on both front and rear needles, said rear starting with the maximum number of needles employed in the high splice and gradually transferring end needles to the front half knitting action until the minimum number of needles employed in the high splice is reached, and continuing the bottom foot portion on said minimum number of needles.
2. A high splice split-foot stocking having a narrowed-and-widened heel pocket and a high splice heel and split foot sole corresponding in width with said heel pocket, and additional reinforcing wales of gradually varied length forming connecting triangular shaped reinforcements extending between said high splice and split sole with their apexes corresponding with the apex points of the heel.

In testimony whereof I affix my signature.

WILLIAM L. LENGEL.
